US0D1001192S

(12) **United States Design Patent** (10) **Patent No.:** **US D1,001,192 S**
(45) **Date of Patent:** **** Oct. 10, 2023**

(54) **CONTROLLER**

(71) Applicant: **SZ DJI Technology Co., Ltd.**,
Shenzhen (CN)

(72) Inventors: **Jaewan Jeong**, Shenzhen (CN);
Jinwook Lim, Shenzhen (CN); **Yanyao He**, Shenzhen (CN)

(73) Assignee: **SZ DJI Technology Co., Ltd.**,
Shenzhen (CN)

(**) Term: **15 Years**

(21) Appl. No.: **29/844,821**

(22) Filed: **Jul. 1, 2022**

Related U.S. Application Data

(63) Continuation of application No. 29/759,687, filed on Nov. 24, 2020, now Pat. No. 960,243, and a continuation of application No. 29/742,227, filed on Jun. 1, 2020, now abandoned.

(57) **CLAIM**

The ornamental design for a controller, as shown and described.

DESCRIPTION

FIG. 1 is a top front perspective view of a controller showing the claimed design;

FIG. 2 is a top rear perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof; and,

FIG. 8 is a right side view thereof.

The broken lines in the figures show portions of the controller that form no part of the claimed design.

1 Claim, 8 Drawing Sheets
